UNITED STATES PATENT OFFICE.

ALBERT H. DE VOE, OF WESTFIELD, NEW JERSEY, ASSIGNOR TO THE SINGER MANUFACTURING COMPANY, A CORPORATION OF NEW JERSEY.

SHOE-STAYING MACHINE.

Application filed May 3, 1919. Serial No. 294,395.

To all whom it may concern:

Be it known that I, ALBERT H. DE VOE, a citizen of the United States, residing at Westfield, in the county of Union and State 5 of New Jersey, have invented certain new and useful Improvements in Shoe-Staying Machines, of which the following is a specification, reference being had therein to the accompanying drawings.

10 This invention relates to sewing machines and particularly to machines for sewing stays to shoe uppers.

It aims to provide a new and improved construction and arrangement of parts to enable an operator to turn out more and better work than heretofore. To this end it contemplates an improved organization of a strip-guide, strip-feeding mechanism and strip-cutting mechanism which require 20 but a single manual operation on the part of an operator to cut a strip and arrest its advance when one shoe upper, or other article, is about to be completed.

The construction comprises essentially a 25 pivoted strip-guide normally held in a position in which a cutter, located at the delivery end of the strip-guide, is ineffective, and in which a strip-feeding mechanism is effective to advance a strip simultaneously with the 30 body material. The strip-guide may be swung on its pivot to bring the cutter into severing relation with the strip and simultaneously stop the strip's advance. A treadle mechanism, located below the cloth-plate 25 is provided for shifting the strip-guide to its different positions and therethrough governing the effectiveness of the strip-cutter and strip feeding mechanism.

Other objects of the invention will appear 40 in the following detailed description of the drawings in which Fig. 1 represents a sewing machine in front elevation with the invention applied thereto. Fig. 2 represents a plan view of the same with the overhanging 45 arm broken away and the cloth-plate removed for unobstructive view of the new construction. Fig. 3 represents the bottom plan view of the machine shown in Figs. 1 and 2. Fig. 4 shows a feed-dog and the 50 strip-guide of the present invention partly in section with the strip-feeding mechanism exposed to view. Fig. 5 represents a feed-dog supporting bar with a feed-dog and the strip-feeding element of the present in-

vention thereon, a push lever for shifting 55 the strip-feeding element appearing in spaced operative relation therewith, and both parts being shown in perspective. Fig. 6 represents a section through the strip-feeding mechanism and shows the relative arrangement of a wedge and its operating 60 pusher. Fig. 7 shows the strip-guide with the cutter arranged at its delivery end. Fig. 7^a is a longitudinal vertical section through the strip-guide to show the mounting of the 65 ledger-blade of the stay-cutter. Fig. 8 shows in spaced perspective component parts of the cutting mechanism. Fig. 9 illustrates a treadle operable lever for controlling the position of the strip-guide. 70 Fig. 10 is a detail perspective view of the knife as anchored to a stationary pin on the machine frame; this construction being a modification of that shown in Figs. 1 and 2.

The invention is illustrated applied to a 75 chain-stitch machine having a plurality of needles 1, and a corresponding number of loopers 2 which may be actuated in any suitable manner. A feed-dog 3 whose opposite ends are sustained by a U-shaped member 80 or yoke 4 is supported on a feed-dog carrying bar 5 pivoted at 6 to the upper end of a feed-rocker 7 which is actuated through the link 8 from an eccentric on the main-shaft 9 in a manner well known. A presser-foot 10 85 is provided on the lower end of a presser-bar 11 slidably supported in the head 12 depending from an overhanging arm 13 which is supported by the standard 14 formed integral with the base-plate 15, the 90 parts 12 to 15, inclusive, constituting the frame of the machine.

The strip-guide of the present invention indicated generally by the numeral 16, is located in front of the needles adjacent the 95 front edge of the cloth-plate indicated in dotted lines at 17 in Fig. 1. The strip-guide 16 is of the angular form in longitudinal section which is shown most clearly in Fig. 4 and is movably sustained between 100 the pivot bearing screws 18 threaded into spaced bosses which are carried by a supporting plate 19 which is secured by the screws 20 fast to the frame of the machine. A strip-guiding channel indicated at 21 with 105 21' in its receiving end is covered in part by a plate 22 having an elongated stiletto slot 23 and in

part also by an L-shaped member 24 which constitutes a ledger-blade of the cutting mechanism to be subsequently described. The strip-guide has a depending and bent 5 arm 25 which receives the end 26 of a rod 27 slidably mounted transversely of the base 15 of the machine, a coil spring 28 about the rod 27 thrusting against a collar 29 on the rod and normally swinging the bent arm 10 25 as viewed in Fig. 4 in a clockwise direction to hold the strip-guide raised. The rear end of the rod 27 is sustained by a plate 30 secured by the screws 31 to the base-plate 15 and this plate 30 also holds in a 15 groove 32 in the base-plate 15 a second rod 33 having a beveled extremity 33' which is adapted to shift the rod 27. The rod 33 has one end caught in a link 34 pinned at 35 to a lever 36 which is fulcrumed on the 20 stud-screw 37 disposed horizontally transverse the main-shaft 9, its apertured end 38 being adapted to receive a connection 39 extending to a foot-treadle or knee shift (not shown). One end of the link 34 is 25 forked as indicated at 34' to embrace a pin 40 in a bellcrank 41 whose fulcrum-pin 42 is parallel to the stud-screw 37. The bellcrank 41 is adapted to be connected to the presser-bar 11 to permit lifting the presser- 30 foot in a manner fully disclosed in my Patent No. 1,420,413, dated June 20, 1922. The parts are so arranged that when the apertured end 38 of the lever 36 is swung downwardly the rod 33 has no action upon 35 the strip-guide but that when the lever is swung in the opposite direction the rod 33 will have its beveled end 33' moved against the spring operated rod 27 and there- 40 through will move the lower end of the arm 25 toward the operator and in this way the delivery end of the strip-guide may be depressed from its normal operating position in which it is shown in Fig. 4 down below the surface of the cloth-plate.

45 A cutting mechanism and a strip-feeding mechanism are thrown into and out of effective relation respectively with the strip passing through the strip-guide when the front end of the latter is depressed.

50 The cutting mechanism comprises the before mentioned ledger-blade 24 which is adjustably secured to the top of the strip-guide by the screw-and-slot connections 45 and a second cutting blade 46 having a cutting edge 47 and a forked extremity 48 and secured to the rectangular projection 49 formed on the end of a fulcrum-pin 50 which is encircled by a coiled spring 51 reacting against the bottom of a socket formed in 55 the strip-guide and a collar 52 fast on the end of the pin to hold the blade 46 yieldingly against the forward edge of the ledger-blade 24. Between the cutting blade 46 and the delivery end of the strip-guide 60 65 16 a wear plate 53 of the shape shown in

Fig. 8 is interposed. Forked end 48 of the cutting blade 46 is adapted to embrace either a pin 54 fixed in a standard 55 rising from the base-plate, see Fig. 10, or a pin 56, Figs. 1 and 2, adjustably connected at 70 57 to a lever 58 fulcrumed on a shouldered stud-screw 59 and having a pin 60 extending laterally from its opposite end into the sleeve portion of a strap 61 embracing an eccentric 62 on the end of the main-shaft 9. Through these connections the knife 46 is 75 continually vibrated, its cutting edge 47, however, not crossing the channel 21 of the strip-guide unless the delivery end thereof is depressed. In the alternative form shown 80 in Fig. 10 which is preferable in some respects because it is simpler, the cutting edge 47 of the knife 46 is arranged below and clear of the guiding channel 21 as long as the strip-guide occupies its normal position. When, however, the delivery end of the strip-guide is depressed, the knife 46 and the blade 24 are brought into cooperative 85 cutting relation and this is true whether the cutting blade 46 be vibrating continuously or the once at the time the stay is cut. In both instances the cutting action is manually controlled or governed through depression 90 of the delivery end of the strip-guide.

The member or yoke 4 sustaining the feed-dog 3 is extended forwardly as indicated at 95 63 toward the front of the machine as illustrated best in Figs. 4 and 5 and to this extension at 64 is pivoted a small rocker 65 carrying a strip-feeding element 66 on one 100 of its arms which is yieldingly urged in a clockwise direction as viewed in Fig. 4 by a coiled spring 67 interposed between it and the feed-dog supporting bar extension 63. The strip-feeding element 66 itself is elastic 105 and is projected through a cut out portion 68 in the under side of the strip-guide 16 so that it may engage the under side of a strip which is in the channel 21 of the strip-guide.

110 It is desirable at times to withdraw the strip-feeding element 66 from engagement with the strip to discontinue its advance and to this end a member 69 slidably sustained by a pin 70 sleeved in the extension 63 with a stop collar 71 on its opposite end and normally urged by a coiled spring 72 away from the extension 63 is provided with a wedge indicated at 73 adapted to separate the lower arm of the rocker 65 from the relatively fixed extension 63 of the feed-dog 115 supporting bar and thereby to withdraw the strip-feeding element 66 from engagement with a strip. To shift the member 69 so that the wedge 73 will lower or withdraw the strip-feeding element 66 an angle-lever 74 having a lateral face 75 is fulcrumed at 76 to any convenient fixed part such as the plate 19 supporting the strip-guide and the lower end 77 of the lever 74 is provided with a roller 78 which is adapted to be 120 125 130

struck by a second roller 79 secured to the depending arm 25 of the strip-guide and therethrough to force the wedge 73 between the extension 63 of the feed-supporting member and the lower arm of the rocker 65. Through the described connections it will thus be seen that when the delivery end of the strip-guide is depressed the work-engaging element of the strip-feeding mechanism will be shifted relative to the strip-guide and by its withdrawal from engagement with the strip arrest further advance of the strip.

In the operation of the machine an operator will first introduce a strip of material, or stay as it is called in the trade, into the guiding channel 21, if necessary employing a stiletto for the purpose, until the free end of the strip is beyond the strip-feeding element 66. The strip may then be rapidly advanced to the presser-foot by operating the machine. The operator may then introduce shoe uppers under the presser-foot and superimpose upon their butt or lapped joint, as the case may be, a stay-strip. The machine is then started up and the staying operation performed. When the staying operation has proceeded far enough for the operator to judge about the right length to cut off the stay-strip to suit the uppers being stitched together, the delivery end of the strip-guide may be depressed by foot or knee operation of the lever 36 which will result in severing the strip and simultaneously arresting further advance thereof.

While the invention comprehends in its preferred form the combination of a strip-guide, a cutter and a strip-feeding mechanism as has been fully described above, it will be understood that it comprehends as well the use of the strip-guide in combination with either the cutting mechanism or the strip-feeding mechanism. It also comprehends the use of the cutting and feeding mechanisms without the strip-guide where it will be possible for the operator to use her hands to direct the strip. Reference should therefore be had to the accompanying claims for a fuller understanding of the scope of the invention.

Having thus set forth the nature of the invention, what I claim herein is—

1. In a sewing machine, in combination, movable means for guiding a strip, and means for severing the strip, said last-named means being governed by movement of the first-named means and comprising a cutting element movable with respect thereto.

2. In a sewing machine, in combination, a movable strip-guide, and strip-cutting mechanism comprising a cutting element movable with respect to and rendered effective by movement of the strip-guide.

3. In a sewing machine, in combination, a shiftable strip-guide, strip-cutting mecha-

nism including a pair of cooperating cutting elements one of which is fixed to the strip-guide and the other of which is movably sustained, and means for shifting the strip-guide to bring the cutting elements 70 into cooperative cutting relation.

4. In a sewing machine, in combination, a movable strip-guide, a strip-cutting mechanism including a pair of cooperating cutting blades mounted for operation with their faces in fixed angular relation one of which is fixed to the strip-guide, and means for moving the strip-guide and blade fixed thereto to bring the cutting blades into cooperative cutting relation. 75

5. In a sewing machine, in combination, a movable strip-guide, cutting mechanism including cooperating blades fixed and pivoted respectively to the guide, and means for moving the strip-guide and bringing the 85 blades into cooperative cutting relation.

6. In a sewing machine, in combination, a pivoted strip-guide, cutting mechanism including cooperating blades fixed and pivoted respectively to the guide, and means for moving the strip-guide and bringing the 90 blades into cooperative cutting relation.

7. In a sewing machine, in combination, a movable strip-guide, cutting mechanism including cooperating blades one of which is fixed to the strip-guide and the other of which is movably sustained by the strip-guide, and means for moving the strip-guide to effect a cooperative cutting action of the 95 blades. 100

8. In a sewing machine, in combination, a pivoted strip-guide, cutting mechanism including cooperating blades one of which is fixed to the strip-guide the other of which is movably sustained by the strip-guide, and means for moving the strip-guide to effect cooperative cutting action of the blades. 105

9. In a sewing machine, in combination, a pivoted strip-guide, cutting mechanism including cooperating blades one of which is fixed to the strip-guide the other of which is pivoted to the strip-guide, and means for moving the strip-guide to effect cooperative cutting action of the blades. 110

10. In a sewing machine, in combination, a movable strip-guide having a guiding channel, cutting mechanism including cooperating and relatively movable blades sustained by the movable guide, one of which constitutes a portion of a wall of the guiding channel and the other of which is supported for movement across the channel to cooperate with the first-mentioned blade, and means for moving the guide and for relatively moving the blades whereby a strip 115 may be severed. 120

11. In a sewing machine, in combination, a strip-guide having a blade fixed thereto, a vibratory blade, said strip-guide being normally held in a position where the blade 130

fixed thereto does not coact with the vibratory blade and being movable to bring the blades into cooperative cutting relation.

12. In a sewing machine, in combination, 5 a movable strip-guide, and strip-cutting means pivoted to said strip-guide and rendered effective or ineffective by movement of said strip-guide.

13. In a sewing machine, in combination, 10 a movable strip-guide, cutting mechanism including a blade secured to said strip-guide and a second blade pivoted to said strip-guide, said blades being yieldingly pressed against each other, and means for changing 15 the operative relation of the two blades when the strip-guide is moved so that cooperative cutting action of the blades may be rendered possible or impossible, and means whereby the strip-guide may be moved.

14. In a sewing machine, in combination, 20 a movable strip-guide having a blade fixed thereto adjacent its delivery end, a second blade cooperatively arranged with respect to the first-mentioned blade, means for continuously operating said second blade, means normally holding said strip-guide where the blade carried thereby is not crossed by the continuously operated blade, and means whereby said strip-guide may be moved to 25 render the blades effective for severance of a strip.

15. In a sewing machine, in combination, 30 a strip-guide having a blade fixed thereto, a second blade, a main-shaft, connections between the main-shaft and the second blade for actuating the latter, and means for moving the first-mentioned blade into cooperative cutting relation with the second blade.

16. In a sewing machine, in combination, 35 a movable strip-guide, a blade fixed thereto, a second blade movable independently of the guide, a main-shaft, an eccentric on said main-shaft, connections between the eccentric and the second blade for moving the latter, and means whereby the strip-guide may be moved to render the blades effective or ineffective for severance of a strip.

17. In a sewing machine, in combination, 40 a strip-guide, a blade connected thereto, a second blade, a lever for vibrating the second blade independently of the guide, means for actuating the lever, and means whereby the strip-guide may be moved to render the blades effective or ineffective.

18. In a sewing machine, in combination, 45 work-advancing mechanism including a feed-dog, a feed-dog supporting member, a strip-feeding element on said member spaced from said feed-dog, a movable strip-guide overhanging said strip-feeding element and means for rendering said strip-feeding element ineffective by movement of the strip-guide.

19. In a sewing machine, in combination, 50 60 means for advancing work a stitch length

at a time, additional means for advancing a strip at substantially the same rate as the work, means for guiding the strip, and means controlled by movement of the strip-guiding means for discontinuing effective 70 action of the strip-feeding means.

20. In a sewing machine, in combination, 75 a movable strip-guide, means for advancing work a stitch-length at a time, additional means for feeding a strip in unison with the work-advancing means, and means controlled by movement of the strip-guide for stopping the feed of the strip.

21. In a sewing machine, in combination, 80 work-advancing mechanism including a feed-dog, a strip-guide, step-by-step strip-feeding mechanism located in advance of the feed-dog, and means for discontinuing the step-by-step advance of the strip.

22. In a sewing machine, in combination, 85 work-advancing mechanism including a feed-dog, a strip-guide, step-by-step strip-feeding mechanism located in advance of the feed-dog, and manual means for discontinuing the step-by-step advance of the strip. 90

23. In a sewing machine, in combination, 95 work-advancing mechanism including a feed-dog, a strip-guide, step-by-step strip-feeding mechanism located in advance of the feed-dog, and treadle operable means for discontinuing the step-by-step advance of the strip.

24. In a sewing machine, in combination, 100 work-feeding mechanism, shiftable means for guiding a strip, means in addition to the work-feeding mechanism for feeding the strip, and means controlled by the shiftable means for guiding the strip for stopping effective action of the strip-feeding mechanism at intervals. 105

25. In a sewing machine having stitch-forming and work-advancing mechanism, in combination, a movable strip-guide, strip-feeding mechanism controlled by movement of the strip-guide, and means whereby the strip-guide may be moved to render the strip feed effective or ineffective. 110

26. In a sewing machine, in combination, 115 a movable strip-guide, step-by-step strip-feeding mechanism including an element arranged to engage the strip, means for relatively shifting said element and said strip-guide to render the element ineffective upon the strip.

27. In a sewing machine, in combination, 120 a movable strip-guide, step-by-step strip-feeding mechanism including an element arranged to engage the strip internally of the strip-guide, a wedge for relatively shifting said element and guide to discontinue feeding of the strip. 125

28. In a sewing machine, in combination, 130 a movable strip-guide, step-by-step strip-feeding mechanism including a strip-engaging element, a wedge for moving the element

- away from engagement with the strip, a thrust-member for shifting the wedge, and means connected to the strip-guide for operating the thrust-member when the strip-guide is moved. 5
29. In a sewing machine, in combination, a movable strip-guide, a strip-feeding member yieldingly held in feeding relation with a strip, means operable by movement of the strip-guide for shifting the member from feeding relation with the strip. 10
30. In a sewing machine, in combination, a movable strip-guide, a strip-feeding member yieldingly held in feeding relation with a strip, a wedge for shifting the member away from feeding relation with the strip, a spring for normally holding the wedge retracted, a pivoted push-lever for operating the wedge, and means connected to the strip-guide for operating the lever. 15
31. In a sewing machine, in combination, manually controlled strip-cutting mechanism, power-driven strip-feeding means including a strip-engaging device, and means connected to the strip-cutting mechanism for withdrawing said device from engagement with the strip to discontinue advance of the strip when it is severed by the strip-cutting mechanism. 20
32. In a sewing machine, in combination, stitch-forming mechanism, work-advancing mechanism, additional feeding mechanism in advance of and acting in unison with said work-advancing mechanism, cutting mechanism located between said work-advancing mechanism and said additional feeding mechanism, and means for rendering the additional feeding mechanism and the cutting mechanism effective in alternation so that when one is effective the other is not effective. 25
33. In a sewing machine, in combination, strip-feeding mechanism, a vibratory blade, means for actuating said blade, a ledger-blade shiftable into and out of effective cooperative relation with respect to said vibratory blade, and means whereby said ledger-blade may be shifted and said strip-feeding mechanism simultaneously rendered effective or ineffective. 30
34. In a sewing machine, in combination, power operated strip-feeding mechanism including a reciprocating strip-engaging member normally acting to advance a strip step-by-step, a strip-cutting device normally ineffective upon the strip and manually controlled means for rendering said reciprocating strip-engaging member ineffective to feed the strip without arresting its motion and for simultaneously operating the strip-cutting device to cut the strip. 35
35. In a sewing machine, in combination, a movable strip-guide, power operated strip-feeding mechanism, and means governed by movement of the strip-guide for severing a strip and rendering the feeding mechanism ineffective. 40
36. In a sewing machine having stitch-forming mechanism and work-feeding mechanism, in combination, means for guiding the strip, means for cutting a strip, and additional power driven means for feeding the strip, the operation of said cutting means and said additional feeding means being governed by movement of the strip-guiding means. 45
37. In a sewing machine having stitch-forming mechanism, in combination, work-feeding mechanism including a feed-dog and a supporting bar therefor, a strip-feeding element movably sustained on and relative to said bar and spaced in advance of said feed-dog, a strip-guide, cutting mechanism including relatively movable blades sustained by the strip-guide one of which is shaped to clear said bar, and means for rendering the cutting mechanism effective and the strip-feeding mechanism ineffective on movement of the strip-guide. 50
38. In a sewing machine having stitch-forming and work-feeding mechanism, in combination therewith strip-guiding, cutting and feeding mechanisms, and manual means for moving the strip-guiding mechanism and therethrough controlling the operation of the strip-cutting and feeding mechanisms. 55
39. In a sewing machine having a cloth-plate, in combination, a strip-guide pivoted adjacent the front of the cloth-plate, an arm connected to said strip-guide, cutting blades located adjacent the delivery end of the strip-guide, strip-feeding mechanism for a work-engaging element located internally of the strip-guide, and connections between said arm and said cutting blades and said feeding mechanism for controlling their action when the strip-guide is moved upon its pivot. 60
40. In a sewing machine, in combination, a movable strip-guide, a strip-cutter, strip-feeding mechanism, said strip-guide having controlling connections extending to said strip-cutter and said strip-feeding mechanism, and means whereby the position of said strip-guide may be altered including a spring normally holding the strip-guide in one position and a treadle connection for shifting the strip-guide against the action of said spring. 65
41. In a sewing machine having stitch-forming and work-advancing mechanism and a cloth-plate, in combination, a movable strip-guide located adjacent said cloth-plate, strip-cutting mechanism operatively arranged adjacent said cloth-plate, strip-feeding mechanism operatively arranged underneath said strip-guide, and means located below said cloth-plate whereby variation of the effectiveness of the strip-cutting and strip-feeding mechanisms may be controlled. 70

42. In a sewing machine, in combination, a movable strip-guide, a strip-cutter, strip-feeding mechanism, connections between said cutter and strip-feeding mechanism and said guide for altering their operative relation when one of them is moved, and means whereby that one of them may be moved. 25
43. In a sewing machine, in combination, a movable strip-guide, a strip-cutter, strip-feeding mechanism, controlling connections from the cutter and feeding mechanism to the strip-guide, and means including angularly disposed slide-rods and a lever for operating one of said rods whereby the strip-guide may be moved to vary the effectiveness of the cutter and strip-feeding mechanism. 30
44. In a sewing machine, the combination with a sewing head having stitch-forming mechanism including a reciprocating needle and work-feeding mechanism including a feed-dog, of a stay-feeding element mounted on the sewing head in advance of the feed-dog and connected to be operated by said work-feeding mechanism, and means inter- 35
- mediate the feed-dog and stay-feeding means for severing the stay-strip. 40
45. In a sewing machine, the combination with a sewing head having stitch-forming mechanism including a reciprocating needle and work-feeding mechanism including a feed-dog, of stay-feeding means mounted in the sewing head and located in advance of the feed-dog, means intermediate the feed-dog and stay-feeding means for severing the stay-strip, and means for rendering the stay-feeding means ineffective when the stay is severed. 45
46. In a sewing machine, a four-motion feed-dog including operative forwardly and rearwardly disposed work-engaging elements, means for rendering the forward work-engaging element effective or ineffective at the will of the operator, and a work-severing implement adapted to operate intermediate said work-engaging elements. 45

In testimony whereof, I have signed my name to this specification.

ALBERT H. DE VOE.
